UNITED STATES PATENT OFFICE

WILLIAM F. CLAYTON, OF HUNTSVILLE, ALABAMA, ASSIGNOR OF ONE-SIXTH TO WILLIAM E. JAMES, OF CULLMAN, ALABAMA, ONE-SIXTH TO NEPHANUS E. JAMES, OF BIRMINGHAM, ALABAMA, AND ONE-THIRD TO R. E. SMITH, OF HUNTSVILLE, ALABAMA

AUTOMATIC THIN-PLACE PREVENTER

Application filed August 2, 1928. Serial No. 297,020.

This invention relates to new and useful improvements in thin place detectors for looms, and has for its principal object the provision of means actuated through the detection of a thin spot, for supplementing the functioning of the weft fork which normally activates the replenishing mechanism of the loom, when through some abnormal condition, the weft fork continues in its normal position, notwithstanding that the weft thread has broken or run out.

Other objects of the invention will appear as the following description of a preferred embodiment thereof proceeds.

15 In the drawings:

Figure 1 is a perspective view of a loom in cooperative association with the mechanism of the present invention;

Figure 2 is a perspective view of the mechanism of the present invention abstracted from what is old and well known in loom mechanism;

Figure 3 is a cross section showing that part of the invention and the loom mechanism on the side remote from the detector finger;

Figure 4 is a view similar to Figure 3, showing the snake head and weft fork disengaged, this being the normal position of the parts when the loom is weaving;

Figure 5 is a perspective view of the weft fork;

Figure 6 is a plan view of that part of the thin spot detector adjacent the detector finger;

Figure 7 is a longitudinal section through the detector arm;

Figure 8 is a side elevation of the resilient articulation between the detector mechanism rocker arm and the detector mechanism itself; and

Figure 9 is a front view of what is shown in Figure 8, the arm 34 being shown in section.

45 Before advertizing to a detailed description of the device of the invention, certain conventional loom structures will be referred to, in cooperation with which by way of example, the present invention functions.

50 In Figures 1 and 4 is shown the oscillating

weft hammer 14 and the weft fork 29 pivotally mounted as at 31 at the rearward end of the slide 20.

Normally the slide 20 occupies an inactive position toward the rearward part 55 of the loom with the fork resting against the weft thread and being thus retained with its tines 29 in a substantially vertical position, while the loop 30 at the upper end of the fork is held above the upper end or snake 60 head 27 of the weft hammer. In the normal operation of the loom, when the bobbin runs out or the weft thread breaks, the fork having its tines no longer restrained by the thread, swings by gravity or perhaps by a 65 light spring so as to depress the loop 30 into the path of the snake head 27, so that the latter, by virtue of its shoulder 26, engages the loop 30 and by this means pulls the fork and with it the slide 20, to which it is pivoted. 70

The slide 20 in moving forwardly operates a bobbin replenishing means, (not shown), through connections 55 and 56, so that the weaving ordinarily proceeds without any 75 thin spot being formed. The slide 20 is, therefore, frequently referred to in the present specification as replenishing mechanism, since it is not considered necessary nor desirable to complicate the disclosure by showing what is old in loom structure. 80

It sometimes happens, however, that because of a bent tine, a bunch of lint collecting behind the weft fork, or for other causes, the fork may remain in its normal position with the loop out of reach of the snake head 85 as though the weft thread were being paid out. Under this condition, there would, of course, be no attempt made by the machine to replenish the weft, and consequently, a thin spot composed of nothing but warp 90 threads is formed in the goods. It is for the purpose of detecting this thin spot and so controlling the loom accordingly, for the reworking of the thin spot that the present invention is designed. 95

The thin spot detector comprises a pawl 28, pivotally mounted on the slide 20 and affording means for moving said slide when said pawl is actuated. Said pawl is adapted to take the place of the loop 30 as an engaging 100

means with the shoulder 26 of the snake head for causing the movement of the slide through which the bobbin is replenished.

The pawl 28 is depressed into active position by means responsive directly to the condition of the cloth at the thin spot, and which means also permits the retrograde movement of the cloth for a distance corresponding to the number of picks missed in the formation 10 of the thin spot, so that the thin spot is filled uniformly with the rest of the cloth by the weft from the fresh bobbin.

Referring particularly to Figure 2, it will be seen that there is a rock shaft 33, suitably secured to a stationary part of the loom as for instance by clips 47. Said rock shaft has rocker arms adjacent its opposite ends, one of which includes the detector arm 34, the opposite rocker arm 39 passing freely 20 through an eye 22 formed in the pawl 28, so that in the normal replenishing movements of the slide 20 under the urge of the loop 30 of the weft fork, there is freedom of relative movement between the pawl and the 25 arm 39. Normally, of course, the resilient finger piece 35 of the detector arm 34 rests upon the cloth and maintains the rock shaft 33 in such position that the rocker arm 39 holds the pawl 28 up in inactive position with 30 respect to the oscillating snake head.

It will be seen from Figures 8 and 9 that the detector arm is connected to the rock shaft 33 by a resilient articulation comprising the 35 cooperating members 61 and 62 pivoted together at 64 and each having a socket receiving respectively, the detector arm 34 and the rock shaft 33, both of said sockets being furnished with means such as setscrews for adjusting them to the elements which they 40 receive. The members 61 and 62 are biased by a spring which contributes to the support of the detector arm while it is upheld by the cloth, while the lower member 62 acts as a limit stop to limit the range of descent of 45 the detector arm so that the finger piece 35 may not fall too far beneath the surface of the cloth upon reaching the thin spot.

The detector arm consists as usual, of two parts adjustably secured by means of a socket 50 37 and setscrew 38, the socket also serving as an abutment for confining the spring 36 which gives resiliency to the finger piece.

A second rock shaft 1 is also provided having a rocker arm 2 at one end, the same constituting a lifter for the detector arm during a certain phase of the operation of the thin spot detector, as will appear.

For this purpose, the rocker arm 2 is provided with an angular end 6 which underlies the detector arm and is adapted to engage and lift the latter when the rock shaft 1 is 55 operated. The rocker arm 2 normally rests upon the cloth out of engagement with the detector arm, which is normally supported by the finger 35 as is well understood.

The opposite end of the rock shaft 1 is provided with a rocker arm 7, which by means of a link 8, is connected to a lifting means for raising the detector finger out of the cloth immediately upon its having dropped into a thin spot. This lifting mechanism comprises a slide bar 9 having a notch 12 forming a shoulder, said notch cooperating with a latch 17 pivotally carried by the pawl 28 and supported by an angular lug 32 which acts to limit the range of movement of said latch in a downward direction. 70 75

When the detector finger 35 has fallen into a thin spot it oscillates the rock shaft 33, rocking the rocker arm 39 downward, thereby depressing the pawl 28 into engagement with the shoulder 26 on the snake head. This causes the slide to which the pawl 28 is connected, and the pawl itself to move forwardly, and since the pawl in becoming depressed has lowered the latch 17 into the path of the shoulder 12, it is obvious that as the slide 20 and pawl 28 move forward the latch 17 will cause the forward movement of the slide bar 9, rocking the arm 7, oscillating the rock shaft 1, and thereby lifting the rocker arm 2 so that the latter engages the detector mechanism and lifts the finger out of the cloth. 80 85 90

The elevating of the detector mechanism causes the oscillation of the shaft 33 in the opposite direction, and lifts the pawl 28 out of engagement with the snake head so that it will be understood that the falling of the detector finger through the cloth is merely 100 for an instant and that it is immediately and positively lifted, so that it may not be entrapped by the newly supplied weft thread. In the meantime, however, the slide has done its duty in supplying a new bobbin to the 105 loom.

The means for letting back the cloth so that the new weft thread can take up the first missed pick is well understood and not shown in the present drawings, being typical 110 of known loom mechanism in which a thin spot detector is employed.

It is sufficient to state that this means operates responsively to the activation of the pawl 28, and the operation of the let-back 115 mechanism permits a retrogressive movement of the cloth due to the tension of the warp threads.

Figures 1 and 2 show that the rock shaft 1 is provided with pivotally mounted supporting pallets 51 and 52, carried by blocks 53 and 54, the first mentioned being slidably adjustable on a rocker arm 3, while the block 54 is adjustable in a similar manner, preferably on the rocker arm 2. 120 125

It will be understood that when the lifting means constituted by the latch 17 and slide bar 9 is actuated, the detector mechanism is supported solely by the rocker arm 2, 130

the pallets 51 and 52 trailing against the surface of the cloth.

It is understood, of course, that the lifting function of the rocker arm 2 is momentary only in its duration, since as soon as the detector mechanism has been raised, the lifting means is released by the elevation of the latch 17, and that the rocker arm 2 is no longer sustained by said lifting means. However, the retrogressive movement of the cloth has been taking place in the meantime, so that the pallets 52 which, in the initial lifting movement have not been burdened with the load of the detector mechanism or its appurtenant elements are moved to a substantially perpendicular position, through their frictional engagement to the cloth so that now they become the sole sustaining means for the rocker arm 2, and finally, when the missed picks have been filled and the cloth changes its direction of movement, the pallets 51 and 52 are drawn out into an inclined position in which they release their support of the detector mechanism letting the detector finger 35 down on the newly woven cloth.

It thus appears that while a lifting means is sudden and instantaneous, the lowering of the detector finger is done gradually and by stages to allow time for the thin spot to be filled.

In this connection, it should be noted that there is preferably, lost motion between the rocker arm 2 and the rock shaft 1, constituted through the fact that the sleeve 59 is loose upon the shaft 1 and provided with a suitable extension 58 forming a stop for engagement with a pin 80 or other suitable means appropriately fixed to the rock shaft 1 so as to permit certain arcuate play between the sleeve and the pin.

Incidentally, the set screw 4 merely plays in a groove, not shown formed in the rock shaft 1 and prevents the sleeve sliding to the leftward as viewed in Figure 2, so that the lifting means 9 and 17 are applied a moment before the lifting of the detector mechanism actually takes place, this interval being allowed to ensure time for the actuation of the bobbin replenishing mechanism.

Since the thin spot detector is designed as an attachment to looms of types now existent a certain tolerance is provided in the range of movement of the latch 17 relative to the slide bar. The latch is constructed to descend as far as is ever necessary in order to engage the shoulder on the slide bar. If, however, the slide bar should be mounted at a less distance from the latch, the pivotal connection between the latch and the pawl 28 permits the latch to come to a stop when it will, regardless of the further depression of the pawl 28.

While I have in the above description defined what I believe a practical and preferred embodiment of my invention, it is to be un-

derstood that the details of construction as illustrated and described are merely by way of example, and not to be considered as having a limitative bearing upon the scope of the appended claims.

What I claim is:

1. In loom mechanism, a detector finger in combination with bobbin replenishing mechanism, means operable responsively to the detection of a thin spot by said detecting finger for actuating said bobbin replenishing mechanism, lifting means for said detecting finger, an operating connection responsive to the actuation of said replenishing mechanism for actuating said lifting means to lift said detecting finger out of the thin spot, said operating connection being severed by the lifting of said detector finger, and means operatively positioned by the retrogressive movement of the cloth for assuming the support of said detector finger when said supporting function is relinquished by the means which is responsive to the actuation of the bobbin replenishing mechanism.

2. In loom mechanism, a detector finger in combination with bobbin replenishing mechanism, means operable responsively to the detection of a thin spot by said detecting finger for actuating said bobbin replenishing mechanism, lifting means for said detecting finger, an operating connection responsive to the actuation of said replenishing mechanism for actuating said lifting means to lift said detecting finger out of the thin spot, said operating connection being severed by the lifting of said detector finger, and means operatively positioned by the retrogressive movement of the cloth for assuming the support of said detector finger when said supporting function is relinquished by the means which is responsive to the actuation of the bobbin replenishing mechanism, said cloth movement responsive supporting means being constructed to withdraw its supporting function from said detector finger, when the latter element is again over the wholly woven cloth.

3. In loom mechanism, a detector finger in connection with bobbin replenishing mechanism, means operable responsively to the detection of a thin spot by said detecting finger for actuating said bobbin replenishing mechanism, said means including a rock shaft having rocker arms adjacent its opposite ends, one of said rocker arms including said detector finger, a pawl operatively associated with said bobbin replenishing mechanism, said pawl being engaged by the opposite rocker arm for depressing said pawl, and means operable responsive to the actuation of said bobbin replenishing mechanism for lifting said detecting finger out of the thin spot, said means comprising a latching element operatively connected to said replenishing mecha-

nism, and a second rock shaft, rocker arms adjacent the ends of said second rock shaft, one rocker arm underlying the rocker arm which includes said detector finger, for lifting the same, and a second latching element operatively connected to the opposite rocker arm on said second rock shaft to be engaged by said first latching element for rocking said second mentioned rock shaft, said underlying rocker arm having a lost motion connection with said second mentioned rock shaft.

4. In loom mechanism, a detector finger in connection with bobbin replenishing mechanism, means operable responsively to the detection of a thin spot by said detecting finger for actuating said bobbin replenishing mechanism, said means including a rock shaft having rocker arms adjacent its opposite ends, one of said rocker arms including said detector finger, a pawl operatively associated with said bobbin replenishing mechanism, said pawl being engaged by the opposite rocker arm for depressing said pawl, and means operable responsive to the actuation of said bobbin replenishing mechanism for lifting said detecting finger out of the thin spot, said means comprising a latching element operatively connected to said replenishing mechanism, and a second rock shaft, rocker arms adjacent the ends of said second rock shaft, one rocker arm underlying the rocker arm which includes said detector finger, for lifting the same, and a second latching element operatively connected to the opposite rocker arm on said second rock shaft to be engaged by said first latching element for rocking said second mentioned rock shaft, and a pallet carried by said second mentioned rock shaft frictionally engageable with the woven cloth and being positioned according to the movement of said cloth for assuming the support of the underlying rocker arm and detector finger when the supporting function has been relinquished by the disengagement of the said latch elements, said pallet moving to a position in which it relinquishes said supporting function altogether, when said cloth again moves in normal direction permitting said detector finger to rest upon said cloth.

one rocker arm underlying the rocker arm which includes said detector finger, for lifting the same, and a second latching element operatively connected to the opposite rocker arm on said second rock shaft to be engaged by said first latching element for rocking said second mentioned rock shaft, and a pallet carried by said second mentioned rock shaft frictionally engageable with the woven cloth and being positioned according to the movement of said cloth for assuming the support of the underlying rocker arm and detector finger when the supporting function has been relinquished by the disengagement of the said latch elements, said pallet moving to a position in which it relinquishes said supporting function altogether, when said cloth again moves in normal direction permitting said detector finger to rest upon said cloth.

In testimony whereof I affix my signature.

WILLIAM F. CLAYTON.
